WRINGER

John S. Visscher, Stratford, Conn., assignor to
General Electric Company, a corporation of
New York

Application April 13, 1938, Serial No. 201,806

4 Claims. (CL. 68—253)

The present invention relates to clothes wringers of the type suitable for use with domestic washing machines.

The object of my invention is to provide an improved construction and arrangement in clothes wringers, and for a consideration of what I believe to be novel and my invention, attention is directed to the following description and the claims appended thereto.

In the accompanying drawings, Fig. 1 is a front elevation of a wringer embodying my invention; Fig. 2 is a sectional view taken on line 2—2 of Fig. 1; Fig. 3 is a sectional view taken on line 3—3 of Figure 1; Fig. 4 is a sectional view taken on line 4—4 of Fig. 2; Fig. 5 is a sectional view taken on line 5—5 of Fig. 4; Fig. 6 is a sectional view taken on line 6—6 of Fig. 4; Fig. 7 is a sectional view taken on line 7—7 of Fig. 6; Fig. 8 is a fragmentary view of the upper end of the wringer along the section line 6—6 of Fig. 4, the parts being shown in the position in which the wringer rolls are pressed together; Fig. 9 is a sectional view taken on line 9—9 of Fig. 3; Fig. 10 is a sectional view taken on line 10—10 of Fig. 9; and Fig. 11 is a sectional view taken on line 11—11 of Fig. 10.

Referring to the drawings, there is shown a wringer having a frame comprising side stiles 1 and 2 connected by a bottom frame member 3 which is bolted to the under side of the side stiles. The side stile 1 is integral with a frame supporting the driving mechanism for the wringer and having a depending tubular sleeve 4 (Fig. 4) which rotatably fits over the upper end of the wringer post 5 of a domestic washing machine and supports the wringer thereon. At the lower end of the sleeve 4 is a flange 6 which rests on a collar 7 fixed to the wringer post 5. The collar 7 has a series of openings 8 which cooperate with the lower end of a detent pin 9 to hold the wringer in one of a plurality of fixed positions. The pin 9 is slidable in a recess 10 in the sleeve 4. It is biased into engagement with the openings 8 by means of a coil spring 11 arranged between the bottom of the recess 10 and the upper end of the pin. The pin is lifted out of engagement with the openings 8 by means of a handle 12 which projects to the outside of the wringer through a slot 13. Movement of the pin 9 is limited by engagement of the handle with the upper and lower edges of the slot.

The wringer is driven by a vertical shaft 14 which is journaled in a bearing 15 at the upper end of the wringer post 5 and which is rotated by any suitable means, for example the driving

mechanism for the washing machine. The upper end of the shaft 14 projects beyond the upper end of the wringer post 5 and fixed thereto is a coupling member comprising a collar 16 having diametrically opposite pin-like projections 17 which fit in slots 18 in the lower end of a tubular coupling member 19. The upper end of the coupling member 19 telescopes over the lower end of a stub shaft 20 which is journaled in a bearing 21 carried in a tubular portion 22 integral with the side stile 1 and forming a continuation of the sleeve 4. The lower end of the shaft 20 is coupled to the coupling member 19 by means of a pin 23 fixed to the coupling member 19 and fitting in a slot 24 in the lower end of the shaft 20. The above described arrangement provides a coupling between the shaft 14 and the shaft 20 which does not require accurate alignment.

On the upper end of the shaft 20 is fixed a bevel gear 25 which meshes at all times with bevel gears 26 and 27 rotatably carried on a splined shaft 28. Between the bevel gear 25 and the upper end of the bearing 21 is a thrust washer 29. The left end of the splined shaft 28 is journaled in a bearing 30 carried on an arm 31 integral with the side stile 1. The right end of the shaft 28 has a cylindrical coupling member 32 pinned thereto which rotates in a bearing 33 carried in a boss 34 in the side stile 1. The bearing 33 therefore serves as a support for the right end of the shaft 28.

The gears 26 and 27 are rotated in opposite directions by the gear 25. The direction of rotation of the shaft 28 can, therefore, be reversed by selectively connecting one or the other of the gears 26 and 27 to the shaft. This is effected by means of a slideable clutch member 35 splined on the shaft 28. On opposite sides, the clutch member is provided with teeth 36 (shown only on the side facing gear 27) which cooperate with recesses 37 in the gears 26 and 27 to couple one of the gears to the shaft 28. In the position shown in Fig. 4 the clutch member 35 is in the neutral position in which the shaft 28 is stationary. The clutch member 35 is moved to the left or right along the shaft 28 to the coupling positions by means of a tongue 38 which fits in an annular groove 39 in the clutch member. The tongue 38 is fixed to the under side of a channel-shaped shifting member 40 which is slideable on bosses 41 and 42. The sliding movement of the shift member 40 is limited by a pin 43 fixed in the boss 41 and projected through an elongated slot 44 in the member 40. The left

end of the member 40 is held against the boss 41 by means of a washer 45 fixed to the projecting end of the pin 43. At the right end of the shifting member 40 is a cylindrical pin-like projection 46 which slidably fits in a channel formed by the depending side walls 47 of a lever 48. Integral with the upper side of the lever 48 is a pin 49 by means of which the lever 48 is pivoted on a bracket 50 fixed to a member 51 slidably carried in a slot 52 (Fig. 8) in the side stile 1. The member 51 is moved in the slot 52 by a projection 53. The bracket 50 and the projection 53 project beyond the edges of the slot 52 on opposite sides of the side stile and therefore serve to hold the member 51 in the slot. The lever 48 is biased to the position shown in Fig. 5 by means of a tension spring 54 arranged between one end of the lever 48 and hook 55 fixed to the arm 31. The spring 54 biases the other end of the lever 48 against the bracket 50, as shown in Fig. 5.

When the parts are in the position shown in Fig. 5 the projection 46 on the shifting member 40 is directly below the pin 49 on the lever 48. In this position the clutch member 35 is in the neutral position in which neither of the gears 26 or 27 is connected to the shaft 28.

When the member 51 is moved toward the left in the slot 52 (downward as viewed in Fig. 5) the lever 48 is moved to a position in which the projection 46 assumes the position with reference to the lever 48 indicated by reference numeral 56 in Fig. 5. During this movement, a force will be exerted on the shifting member 40 tending to move the member 40 to the left, as viewed in Fig. 5, and there will therefore be an equal and opposite force of reaction exerted on the lever 48 which will be toward the right, as viewed in Fig. 5. Under normal conditions, this force will be less than the force exerted by the tension spring 54 and the sole effect will be that the clutch member 35 is moved into engagement with the gear 26 coupling this gear to the shaft 28.

Under some circumstances, the clutch teeth 36 will strike the portions of the gear 26 intermediate the depressions 37, and under these circumstances, further movement of the clutch member toward the engaged position would be impossible. Under these circumstances, the force of reaction exerted on the lever 48 by means of the projection 46 will be of sufficient magnitude to overcome the force of the spring 54 and the lever 48 will accordingly be pivoted about the pin 49 relieving the pressure exerted on the shifting member 40 and preventing damage to the shifting mechanism. The gear 26 is rotating continuously so that the condition in which the clutch teeth 36 are opposite the portions of the gear intermediate the depressions 37 will be momentary, and will be corrected by the rotation of the gear 26. As soon as the depressions 37 of the gear 26 are rotated to a position opposite the clutch teeth 36 the lever 48 will be returned by the spring 54 to the position shown in Fig. 5 thereby completing the movement of the shifting member 40 necessary to move the clutch member 35 to the engaged position. From the above description, it is clear that the clutch member 35 is yieldingly moved to the engaged position with the gear 26.

When the member 51 is moved from the position in which the clutch member 35 is engaged with the gear 26 the lever 48 exerts a force on the pin 46 tending to move the shifting member 40 to the right, as viewed in Fig. 5. There is,

therefore, an equal and opposite force of reaction exerted on the lever 48 acting toward the left. This force will tend to pivot the lever 48 in a counterclockwise direction, as viewed in Fig. 5, and will therefore hold the lever 48 solidly in the position shown in Fig. 5. There is, therefore, no yielding movement of the lever 48 while the clutch member 35 is being moved from the engaged position.

By a similar analysis, it will be found that the clutch member 35 is yieldably moved into engagement with the gear 27 and is positively moved from the engaged position. It is obviously desirable that the clutch member be yieldingly moved into engagement with the gears so as to prevent damage to the mechanism in case the teeth of the clutch member are not properly aligned with the cooperating parts of the gears. However, since there is a possibility that the clutch member may stick in the engaged position, particularly when the clutch member is shifted under heavy load, it is equally desirable that the clutch member be moved from the engaged position positively. Both of these objects are fulfilled in the above described mechanism.

The driving mechanism is enclosed by a shell 57 which is secured to the side stile 1 by means of screws 58. The shell 57 has a skirt 59 depending around the outside of the wringer post and having an opening 60 therein through which the handle 12 projects. It will be noted that with this construction the frame supporting the wringer and driving mechanism therefor is a single casting having a shape chosen solely for its functional purposes. The shell 57, which comprises the rest of the wringer head, serves as an enclosure for the driving and supporting mechanism. The appearance or styling of the shell 57 may, therefore, be changed materially without changing the construction of the driving and supporting mechanism. This is a considerable advantage over the wringer constructions in general use wherein the driving and supporting mechanism is built into a wringer head which also serves as the enclosure for such mechanism.

On each side of the wringer are upper drainboards 61 having tabs 62 at one end which are hooked into slots 63 in the side stile 2 (Fig. 11) and having tabs 64 at the other end which are clamped between the side stile 1 and the abutting edges of the shell 57. Intermediate the tabs 62 and 64 the edges of the drainboards 61 are flush with the side stiles 1 and 2. The drainboards 61 have a rounded upper edge 65 just below the bite of the wringer rolls and an inclined surface leading up to this edge which serves to guide the material to the rolls. The lower edges of the drainboards are rounded and provided with inwardly extending flanges 66. The rounded edges present a smooth surface so that the material being wrung will not be caught on the drainboard.

Beneath the drainboards 61 are lower drainboards 67 which terminate short of the inner edge of the flange 66 so as to provide a drainage space (Fig. 2). The drainboards 67 are connected by an integral channel-shaped portion 68 which encloses and is spaced from the side of the bottom frame member 3. The drainboards 67 have upwardly extending side flanges 69 which are respectively secured to the adjacent side stiles. The water is directed to the drainboard 67 by a tilting drainboard 70 which is supported and tilted in a manner which will be hereinafter described.

Between the side stiles are upper and lower wringer rolls 71 and 72. The lower wringer roll 72 is fixed to a shaft 73 having an integral coupling head 74. The coupling head has a pin 75 fixed therein which cooperates with slots 76 in the coupling member 32 to provide a driving connection between the shaft 28 and the lower wringer roll. At the other end the shaft 73 is journaled in a bearing 77 which is carried in a square bearing block 78, seated in a seat 79 integral with the side stile 2. The seat 79 is open at its upper end.

The upper wringer roll 71 is journaled on a shaft 80 which is fixed between the depending arms 81 and 81a of a control bar 82, extending across the top of the wringer. The control bar is provided at its center with a hand grip 83. The control bar has integral skirts 84 which extend over and partially enclose the upper roll. When the control bar is in the wringing position, shown in Fig. 8, the skirt on the side of the wringer from which clothes are being fed extends in front of the major portion of the upper roll and serves as a guard. Since there is substantially no space between the lower ends of the skirt and the upper roll the operator cannot reach in between the upper roll and the control bar. This is a safety feature since if a greater space were provided the operator's hand might become jammed between the control bar and the upper roll. This would be particularly likely if the operator's hand were inserted between the control bar and the upper wringer roll from the side opposite from that from which clothes were being fed.

The upper roll and the control bar constitute a unitary assembly which can be inserted and removed as a unit. The arms 81 and 81a of the control bar have outwardly extending projections 85 and 85a which fit in slots 86 in vertically slidable plates 87 carried in the inner faces of the side stiles 1 and 2 (Figs. 5 and 11). At the upper end of the slots 86 are hook shaped portions 88 which prevent direct upward movement of the control bar assembly. To insert or remove the control bar, the control bar is tilted so that the projections 85 extend angularly beneath the hook shaped portions 88. The openings provided by the hooked portions 88 are covered by plates 88a hinged to the side stiles 1 and 2.

The lower ends of the plates 87 have openings 89 through which the bottom frame member 3 extends. A pair of leaf springs 90, one of which bears against the lower side of the bottom frame member 3 and the other of which is hooked through the openings 89 bias the plates 87 downward. It will be noted that the force exerted by the springs in the frame is close to the side stiles. There is, therefore, very little danger of distorting the frame due to the spring forces. If the upper spring were omitted, the force exerted on the bottom frame member 3 would be at its center. There would then be some danger of flexing the bottom frame member and thereby causing spreading of the upper ends of the side stiles. The springs are enclosed by the channel shaped portions 68 of the lower drainboards 67. Due to the enclosure, there is substantially no danger from breaking of the springs. The downward movement is limited by stops 91 which are fixed to the upper side of the bottom frame member 3 and which engage the upper edges of the openings 89. Upward movement of the plates 87 is limited by the tension of the leaf springs 90.

The plates 87 are provided with clearance openings 92 around the lower wringer roll shaft 73. The plates 87 are enclosed by cover plates 93 fixed respectively to the side stiles 1 and 2. Roll guards 94 are fixed to the outer surface of the cover plates 93.

The slots 86 in the plates 87 have a central portion 95 in which the lower ends of the projections 85 and 85a loosely rest and branched cam surfaces 96 on each side thereof which cooperate with rollers 97 journaled on shafts 98 fixed in the projections 85 and 85a. When the control bar is in the neutral position, shown in Fig. 6, the rollers 97 are directly above the lower ends of the projections 85 and the control bar assembly is accordingly loosely carried in the wringer. Under these conditions, the plates 87 are urged downward against the stops 91 by the leaf springs 90.

To apply pressure between the rolls the control bar is tilted to one side or the other of the central position. Under these conditions the rollers 97 cooperate with the cam surfaces 96 to force the upper roll against the lower roll. The plate 87 yields upward against the tension of the springs 90 limiting the pressure between the rolls. In the position shown in Fig. 8, the rollers 97 rest in arcuate portions 99 and the direction of the pressure is such that the control bar is held in this position. As varying thicknesses of material are fed between the rolls, the upper roll is forced upward, moving the control bar and plate 87 upward while the parts remain in the same position. To release the pressure between the rolls the control bar is merely returned to the central position, moving the rolls out of engagement with the cam surface 96.

It will be noted that the movement of the upper roll is in a vertical direction while pressure is being applied and released since it is confined by the slots 95. Also, when the rolls are pressed together the angular position of the control bar is independent of the position of the plates 87. It is, therefore, impossible to release the roll pressure by wringing too great a thickness of material. This is due to the fact that in the wringing the control bar is wedged across the slots 95 and the cam surfaces 96, both of which are part of the plates 87. The vertical position of the plates 87 accordingly has no effect upon the control bar.

The tilting movement of the control bar is used to apply pressure between the wringing rolls and is also used to control the driving connection to the lower wringer roll. This is effected by means of an arm 100 projecting from the lower end of the arm 81 and having a projection 101 which fits in a channel shaped slot 102 (Fig. 8) in the part 53 of the slide 51. The channel shaped portion is enlarged at its upper end to facilitate insertion of the projection 101 therein when the control bar is being inserted in the wringer. It is obvious that as the control bar is tilted the slide 51 will be moved in the slot 52. As explained above, this movement of the slide controls the driving connection to the shaft 28. When the control bar is in the central position the slide 51 will be in the center of the slot 52. The parts are designed so that when the control bar is tilted toward the operator the wringer rolls are rotated in the direction to wring material from the side facing the operator.

Since the operation of the wringer is effected by moving the control bar to one side of the central position, it is desirable that accidental movement of the control bar to the operative position

be prevented. This is effected by means of a projection 103 on the lower end of the arm 81a which cooperates with a groove 104 in a strip spring 105. This serves as a detent holding the control bar in the central position. The upper edge of the strip spring 105 is chamfered at 106 to facilitate insertion of the control bar assembly.

During wringing, it is necessary that the drain-board 70 be tilted so as to direct the water to the proper side of the wringer drainboard. The drainboard 70 is pivotally supported on pins 107 integral with the cover plates 93 (Fig. 4). At the free end of the wringer, the drainboard 70 has an upwardly extending ear provided with a channel shaped portion 108 (Fig. 9) which fits over a pin 109 carried on a plate 110 which is rotatable on the lower roll shaft 73. The plate 110 is arranged between the end of the lower wringer roll and the inner face of bearing bar 71. At its upper end, the plate 110 has an inwardly extending tab 111 which extends between the bite of the rolls. The lower end of the plate 110 is heavy enough to bias the plate to a vertical position. The tab 111 is therefore being constantly urged with a relatively light force into the bite of the rolls. When the wringer rolls are reversed the tab 111 is gripped between the rolls and the plate 110 is moved to the opposite side of the drainboard 70 to one side or the other of the central position. The movement of the drain-board 70 is limited by engagement of the front edge thereof with the upper surface of one of the drainboards 67. This edge is covered by a rubber strip 112 which serves as a seal. Movement of the plate 110 beyond the position necessary to effect the tilting of the drainboard 70 is prevented by engagement of the pin 109 with an inwardly extending tab 113 at the upper end of the channel shaped portion 108.

What I claim as new and desire to secure by Letters Patent of the United States is:

1. In a wringer, rolls, driving gearing therefor including a member movable into and out of a position effecting a driving connection to the rolls, mechanism for applying and releasing the pressure between the rolls, a carrier reciprocated by said mechanism, a lever pivoted thereon, means yieldingly resisting pivotal movement of the lever in one direction and offering substantially greater resistance to pivotal movement thereof in the reverse direction, a connection between said lever and said movable member whereby the movable member is moved into and out of the driving

position as the carrier is reciprocated, said connection being shiftable along the length of the lever.

2. In a wringer, a reversible drive for the rolls including a member shiftable from one to the other side of a neutral position to effect driving connections respectively rotating the rolls in one or the reverse direction, a lever pivoted intermediate its ends, means yieldably resisting pivotal movement of the lever in one direction, means offering substantially greater resistance to pivotal movement of the lever in the opposite direction, and shifting means for said member acting through a connection between the lever and said members, said connection being movable relative to the lever and being on one or the other side of the pivot point of said lever as said member is shifted respectively on one or the other side of this neutral position.

3. In a wringer, a reversible drive for the rolls including a member shiftable from one to the other side of a neutral position to effect driving connections respectively rotating the rolls in one or the reverse direction, mechanism for shifting said member including a lever pivoted intermediate its ends, means yieldably resisting pivotal movement of the lever in one direction, means offering substantially greater resistance to pivotal movement of the lever in the opposite direction, a connection between said member and said lever, and means for effecting movement relative to the lever of said connection and the pivot point of the lever so said connection is shifted from one to the other side of the pivot point as said member is shifted from one to the other side of the neutral position.

4. In a wringer, a reversible drive for the rolls including a member shiftable from one to the other of a neutral position to effect driving connections respectively rotating the rolls in one or the reverse direction, a lever pivoted intermediate its ends, means yieldably resisting pivotal movement of the lever in one direction, means offering substantially greater resistance to pivotal movement of the lever in the opposite direction, a cam surface on said lever extending on each side of the pivot point of the lever, a cam follower on said member cooperating with said cam surface, and means for shifting said lever to bring the cam follower on one or the other side of the pivot point of said lever as said member is shifted respectively on one or the other side of the neutral position.

JOHN S. VISSCHER.
